UNITED STATES PATENT OFFICE

TIMOTHY E. SHEA, OF RUTHERFORD, NEW JERSEY, ASSIGNOR TO WESTERN ELECTRIC COMPANY, INCORPORATED, OF NEW YORK, N.Y., A CORPORATION OF NEW YORK

WAVE TRANSMISSION

Application filed June 19, 1925. Serial No. 38,134.

This invention relates to wave transmission, and particularly to selective circuits for separating carrier waves of different frequencies.

5 An object of the invention is to improve the selective transmission of the different channel frequencies in a carrier signaling system without materially affecting the transmitting bands of the filters employed 50 therein.

10 A related object of the invention is to prevent singing in two-way repeaters of the type commonly employed to repeat waves of different frequencies in two directions.

15 The invention is adapted for use in multiplex carrier telephone and telegraph systems operated on a group frequency basis, wherein the different channel frequencies transmitted in one direction are grouped in 20 a different frequency range from that employed for transmission in the opposite direction.

25 In systems of this type, the necessity of including a large number of channels within a somewhat limited overall frequency range makes it difficult to design directional filters because of the extremely large change in the transmission loss that is required in a relatively small frequency interval.

30 In order to prevent singing in two-way repeaters, the total loss in the loop circuit formed by the oppositely directed repeating channels must exceed the total gain of the amplifiers. Because of the difficulty in making the filter loss characteristics change rapidly enough to give a high loop loss, between their cut-off frequencies, however, singing may frequently occur within the repeater at a point between the upper and 35 lower transmission bands where the loss introduced by the filters is small.

40 In accordance with the present invention, this difficulty is overcome by means of a tuned circuit inserted at the junction point 45 of the directional filters and designed to

resonate at some frequency in the region between the upper and lower transmission bands in the frequency scale. This added impedance is designed to add to the loss in this region without affecting the loss in the transmission bands of the filters.

The invention will be described in connection with the accompanying drawing in which:

Fig. 1 is a diagrammatic illustration of a 55 two-way repeater embodying the invention, in which the repeating channels are connected in series with the transmission line.

Fig. 2 shows a modification of the circuit of Fig. 1, in which the repeating channels 60 are connected in parallel with the transmission line.

Figs. 3 and 4 show curves illustrating the principle of operation of the repeaters of Figs. 1 and 2. 65

The two-way repeater of Fig. 1 comprises two one-way repeating channels RW and RE, adapted to connect transmission line sections W and E.

The currents incoming at the repeater 70 from line section E are amplified in the channel RE and the amplified currents are delivered to line section W. Similarly, the currents incoming from line section W are amplified in the channel RW and the amplified currents are delivered to line section E. 75

The currents incoming from the line section W are of higher frequencies than those incoming from line section E. The respective repeater channels are provided with 80 frequency discriminating filters which direct the incoming currents to the proper channels.

The repeater channel RW includes a high pass input filter HPIF, an amplifying structure WA, and a high pass output filter HPOF. The repeater channel RE includes a low pass input filter LPIF, an amplifying structure EA, and a low pass output filter LPOF. Filters HPIF and LPIF are con- 85 90 95

nected in series with line section W, while filters HPOF and LPIF are similarly connected to line section E.

The amplifying structures WA and EA 5 may be of any well-known type such, for example, as that disclosed in U. S. Patent No. 1,413,357 to P. A. Raibourn, issued April 18, 1922.

The directional filters HPIF and HPOF 10 are designed to transmit currents of the upper group of frequencies assigned to channel RW, and to suppress from transmission currents of lower frequencies, while the directional filters LPIF and LPOF are 15 designed to transmit currents of the lower group of frequencies assigned to channel RE and to suppress currents of higher frequencies. These filters may be of the general type disclosed in U. S. Patent No. 20 1,227,113 to G. A. Campbell, issued May 22, 1917.

In designing the high and low pass filters for channels RW and RE, respectively, it is difficult to make the filter loss characteristics rise rapidly enough to give a high loop loss in the available frequency interval. This is shown graphically by the filter curves of Fig. 3, wherein the transmission loss of the filters is plotted against frequency.

The curves hp and lp represent the transmission loss characteristics of the high and low pass filters, respectively. The sum fl of the transmission losses of the high and 35 low pass filters forming the repeater group, drops to a minimum between the transmission bands of the filters, and may drop to such a low value as to permit singing within the repeater as a result of regeneration.

40 In order to increase the loss in this region, a loop tuned circuit 1, comprising a low inductance and large capacity, is inserted in series with the filters HPIF and LPOF of Fig. 1, a similar tuned circuit being inserted at the junction point of filters HPOF 45 and LPIF. The added tuned circuits are identical and, as indicated by the resonance curve te of Fig. 4, are designed to resonate at some frequency in the region between the 50 transmission bands of the high and low pass filters. The sum of the transmission losses of the filters and the tuned circuit causes a substantial total loss tl in this region without affecting the transmission bands of the 55 filters.

Fig. 2 shows a modification of the invention in which the repeater directional filters are connected in parallel with the transmission line. In this case, a so-called "stiff circuit" 3, comprising a large inductance and a small capacity is connected in parallel with filters HPIF and LPOF, a similar tuned circuit 4 being inserted at the junction point of filters HPOF and LPIF.

60 In wave transmission circuits such as are

shown in Figs. 1 and 2, where two or more filters are connected either in series or in parallel to a common transmission line, it is customary to terminate the filters at the ends where they are joined together in a fractional termination designed to improve the loss characteristics of the filters, as disclosed in an application of O. J. Zobel, Serial No. 377,965, filed April 30, 1920, which became Patent No. 1,557,230, October 13, 1925. Small reflection losses occurring near the cut-off points of the filters due to the presence of the tuned circuits illustrated in Figs. 1 and 2 may therefore be taken into consideration in determining the proper termination of the filters themselves. 70 75 80

The elements herein shown and described are considered as merely illustrative of the invention which, of course, is susceptible of various other modifications and adaptations. 85

What is claimed is:

1. A wave transmission system including a plurality of filters for transmitting mutually exclusive bands of frequencies, and means comprising a tuned circuit to introduce a substantial transmission loss in the frequency region between said bands of frequencies. 90

2. A wave transmission system including a transmission line, a plurality of filters connected in parallel circuit relation to said line for transmitting mutually exclusive bands of frequencies, and means to introduce a substantial transmission loss in the frequency region only between said bands of frequencies comprising an impedance element connected to said filters. 95 100

3. A wave transmission system including a transmission line, a plurality of filters connected to said line for transmitting mutually exclusive bands of frequencies, and a selective circuit directly connected to said filters to introduce a substantial loss at frequencies intermediate said bands of frequencies. 105 110

4. A wave transmission system including a transmission line, a pair of directional filters for transmitting mutually exclusive bands of frequencies associated with said line, and a tuned circuit inserted at the junction point of said filters and designed to resonate at some frequency in the region between the upper and lower transmission bands in the frequency scale. 115

5. In a two-way repeater for coupling two transmission lines over which the waves transmitted in one direction are of higher frequencies than those transmitted in the opposite direction, high and low pass filters for separating the directional frequencies, and means comprising a tuned circuit for causing a substantial loop loss in the frequency region between the transmission bands of said filters. 120 125

6. In a two-way repeater for coupling

two transmission lines over which the waves transmitted in one direction are of higher frequencies than those transmitted in the opposite direction, high and low pass filters for separating the directional frequencies, and a tuned circuit inserted at the junction point of said filters and designed to introduce a substantial loop loss in the region between the transmission bands of said filters.

10 7. A wave transmission system comprising a transmission line over which the waves transmitted in one direction are of higher frequencies than those transmitted in the opposite direction, a repeater including high and low pass filters connected in series to said transmission line, and an impedance connected in series with said filters and adapted to introduce a substantial transmission loss in the frequency region between the transmission bands of said filters.

In witness whereof, I hereunto subscribe my name this 16th day of June A. D., 1925.

TIMOTHY E. SHEA.
